UNITED STATES PATENT OFFICE

JULIAN L. PERKINS, OF WEST SPRINGFIELD, AND HIRAM D. CROFT, OF SPRINGFIELD,
MASSACHUSETTS

WRINGER

Application filed August 6, 1931. Serial No. 555,612.

This invention relates to improvements in wringers, and is directed more particularly to improvements in wringers having safety features associated therewith.

5 The principal objects of the invention reside in the provision of a wringer wherein a pair of coacting rolls are releasably held in operative engagement with certain parts readily accessible to the operator for manual manipulation whereby the operator may easily and quickly release the rolls from operative engagement.

Another object of the invention is the provision in a wringer of driving mechanism which is simultaneously disengageable as the rolls are released from operative engagement, all to the end that the operator is safeguarded against injury.

Various novel features and advantages of 20 the invention will be more fully hereinafter referred to in connection with the accompanying description of the preferred form of the invention taken in connection with the accompanying drawings which show a novel 25 combination and arrangement of parts.

In the drawings:

Fig. 1 is a plan view of a wringer apparatus embodying the novel features of the invention.

30 Fig. 2 is a side elevational view of the same. Fig. 3 is an end elevational view of the right hand end of the wringer shown in Fig. 2.

Fig. 4 is an enlarged partial sectional and 35 side elevational view of the wringer shown in Fig. 2.

Fig. 5 is a sectional elevational view taken on the line 5—5 of Fig. 4, showing certain modifications of the invention.

Fig. 6 is an enlarged sectional plan view 40 at one end of the wringer taken on the line 6—6 of Fig. 7.

Fig. 7 is an elevational sectional view on the line 7—7 of Fig. 6.

Fig. 8 is a fragmentary partial sectional 45 view showing a modified form of certain of the details of the wringer structure.

Referring now to the drawings more in detail the invention will be fully described.

50 There is shown in Figs. 1 and 2 a wringer apparatus which may include a so-called head

2 and a wringer indicated generally by 4. It is usual to provide the wringer head with driving mechanism while the wringer is supported and driven therefrom in some suitable manner.

55 The wringer head 2 shown consists of a casing or housing 6, which has a depending tubular portion 8 for resting on an upper flange 10 of a supporting tube 12 usually associated with a washing machine or the like. 60 As shown the housing 6 is usually rotatable relative to the tube 2 and means to be described is provided to lock the housing to the tube 12.

The tube 12 has rotatable therein a drive 65 shaft 14 and in this case the said shaft may carry a part 16 rotatable in a suitable bearing 18 at the upper end of the tube 8. A driving member in the form of a pinion 20 is carried at the upper end of the shaft 14 70 for driving the wringer apparatus.

A cam member 20 is oscillatable and reciprocable in the housing 6 and is hollowed out to receive driven gears 22 and 24 which are slideable and non-rotatable on a shaft 26. 75 A non-round shaft such as shown is suitable, but the gears and shaft may have keys and slots associated therewith.

The shaft 26 has one end 28 rotatable in a suitable bearing carried by a cap 31 for 80 the housing and its other end 29 is receivable in a tube or sleeve 30.

A pin 34 and angularly disposed slot 36 associated with the cam member 20 and the upper side of the housing are arranged so 85 that the cam member is reciprocated relative to the housing as it is oscillated or rotated. As it reciprocates in one direction or the other the gears 22 and 24 are moved thereby into and out of engagement with the drive pinion 20. Accordingly as one or the other of the gears 22 and 24 are brought into engagement with the pinion the shaft 26 will be driven in one direction or the other.

90 As shown in Fig. 4, the gear 22 is in mesh with the pinion 20 so that with the shaft 14 rotatable in a certain direction the shaft 26 will be rotated in a certain direction. These gears 22 and 24 are held in a spaced relation by means of a sleeve 25 therebetween as 95 100

shown and with both the gears 22 and 24 out of engagement with the pinion 20 the driving mechanism is in what may be called a neutral or inoperative position.

5 The member 30 is rotatable in a barrel 40 which is oscillatable with the cam member 20 and housing 6 and is arranged as by pin 42 to be driven by the shaft 26.

10 The sleeve 30 is hollow as shown to receive an inner end 36 of a roll shaft 38. A nut 40 on the end of the shaft may fit in a suitable bore of the sleeve or some other means may be employed whereby the shaft 38 will be rotated by the sleeve 30.

15 The barrel 40 previously referred to and which is oscillatable relative to the housing is held against axial displacement in the housing by means of a flange member 50. This flange member 50 may be a part of a frame 20 F of the wringer, and is secured to the end of the housing 6 by means of suitable bolts or screws 52 or the like.

25 A pin 54 is carried by the cam member 20 and works in a suitable bore in the member 40 so that as member 40 is oscillated the member 20 will be oscillated thereby while at the same time the member 20 may reciprocate in the housing quite independently of the member 40.

30 A fork or yoke member 60 such as shown in Figs. 4 and 7 is secured by means of screws 62 to the member 40. This fork 60 has an open ended slot 66 in the upper end which is directed upwardly for receiving a part associated with a driven roll as will later be described.

35 As the member 60 is swung in one direction or the other the member 40 is oscillated to oscillate member 20. As the member 20 is oscillated it is reciprocated in the housing 6 by means of the pin and slot arrangement described so as to move the gears 22 between a neutral position and a position where either one or the other of the gears meshes with the 45 drive gear 20.

40 A detent 41 in a bore 43 of the housing at the lower side thereof is urged by a spring 45 so as to engage a socket 47 of the member 20. The bore and socket are arranged so that 50 the detent functions to yieldably hold the member 20 in a neutral position when the gears 22 and 24 are out of engagement with gear 20.

45 The wringer frame F may take any form desired, but in the form of the invention shown in Fig. 2 it has upwardly extending end portions 70 which may be hollowed out as in Fig. 7. Bolts 72 are slideable therein and have springs 74 disposed between heads 60 or nuts 76 and shoulders 78. These springs urge the bolts downwardly and the upper ends of the bolts are pivoted at 80 to cross bars or saddles 82, as shown in Fig. 7.

55 A driving roll 90 is carried by the shaft 38 which extends between the end portions 70

of the wringer frame and is suitably journaled in the outermost portion 70.

A driven roll 92 which is entirely separable from the wringer and lower driving roll 90 is receivable in the saddles 80 and is releasably held therein for operative engagement with the lower drive roll. By releasing the roll 92 from the members 82 the operator of the wringer is safeguarded and the means for releasably holding the roll 92 in the saddles and in operative engagement with the drive roll will now be described.

The members 82 are provided with vertically disposed slots 100 on their adjacent inner sides for receiving the ends of the roll 92. As shown in Fig. 7, the side walls of the slots 100 are provided with circular or curving seats 102. The roll 92 has a shaft 103 which carries inner races 104 of ball bearings, hubs or the like. An operating bar structure 80 110 extending from end to end of the roll 92 has end portions or arms 112 which are journaled on the parts 104 described whereby the roll and shaft are rotatable relative to the member 110.

90 The operator may by grasping the member 110 lower the roll 92 into place. The ends of the roll may be dropped downwardly into the slots 100 of the saddle members and when the roll 92 contacts with the roll 90 the member 110 is swung downwardly. Cam faces 120 on the saddles adjacent the seats are arranged to coact with cams or studs 122 on the member 110. The cams and cam faces are arranged so that as the member 110 is swung 95 downwardly the roll is moved sideways of the slots 100.

100 In moving sideways the part 112 of the member 110 enters a seat 102 and by means of the cam arrangement described the roll 92 is releasably held in the seat and in operative engagement with the drive roll 90.

105 With the roll 92 removed from the wringer the yoke 60 is disposed in a neutral position centrally of the slot 100. In this position the gears 22 and 24 are out of operative engagement with pinion 20.

110 As the roll 92 is lowered into the slots 100, as described, a part 111 associated therewith or with its shaft is received by the yoke. As the roll is moved sideways of the slot 100, as described, the yoke is swung thereby so as to oscillate member 40 and cam 20 which is simultaneously reciprocated to bring gear 22 or 24 into mesh with pinion 20 whereby the lower 115 roll is driven for driving the upper roll.

120 The parts are shown in Fig. 7 in operative relation and the shaft 14 may be driven in such a direction that the rolls 90 and 92 will be driven in the direction of the arrows shown in said Fig. 7, and in which case the operator will ordinarily stand at the left of the parts as shown. In this position should it be necessary to release the roll 92 from operative engagement, the operator may by con- 125 130

tacting with the member 110 urge it either up or down so that the stud 122 runs off the cam face 120. This will allow the roll 92 to move inwardly as it is no longer held and 5 clothes or anything else between the rolls will force the roll 92 upwardly. By this movement of the member 110 either in an upward or downward direction, whichever the operator may find most convenient and by 10 means of a cam 119 associated with the arm 112 which will strike upon or against the inner side of the slot 100 the roll moves inwardly of the slot so as to be free to move upwardly. In this way objects between the 15 rolls are relieved of pressure.

It is noted that since the saddles are yieldingly held against upward movement that the roll 92 is yieldingly held in operative position against the roll 90 therebelow. In this 20 way the rolls are capable of receiving therebetween various thicknesses of material for a proper wringing action.

A drain board 130 as shown in Figs. 4 and 7 is disposed between the ends of the frame 25 70 and is pivoted as at 132 for tilting movements. A lug 134 extending upwardly at one end thereof is disposed in the path of a member 136 associated with the shaft 38. These parts are so arranged that in the rotation of 30 the shaft 38 the member 136 will abut the member 134 to tilt the member 130 as shown in Fig. 7. Should the shaft and roll rotate in opposite directions the parts are so arranged that the drain board will be tilted in 35 an opposite direction.

In lieu of the pin connections shown in Fig. 7, the bolts 72 and saddles 70 it may be desirable to provide an enlarged part 140 on the upper end of the bolt which will seat 40 in a suitable socket provided in the saddle 82.

A bolt 170 is slidable at upper and lower ends in the housing 6 and a lug 171 as shown in Fig. 4. Its lower end is arranged to lock 45 in an opening of an arm 172 of the tube 12. When so locked the housing and wringer are held against relative rotation.

An opening 173 is provided in the lower side of the cam 20 to receive the upper end 50 174 of the bolt. This opening is disposed in such a way that it is above the rod only when the cam 20 is in an inoperative neutral position and in that position only may the bolt 107 be raised to allow the head to turn 55 relative to the tube 12.

In an operative position of the parts shown the head is locked against rotation. When the cam is in a neutral position the bolt may 60 be elevated to allow the head to rotate.

A spring 175 between the housing and a hand grip 176 on the rod urges the bolt downwardly so that a pin 177 abuts the arm 171.

By the means of the bolt it is impossible 65 to move the head while the wringer is in

operation which is desirable for safety reasons.

In describing the operation of the apparatus it will be assumed that the upper roll 92 has been separated from the wringer. With 70 this roll separated from the wringer the yoke 60 is in a neutral position so that its open upper side is centrally of the slots 100 of the saddle members 82. In this neutral position the cam member 20 is located so that neither 75 of the gears 22 and 24 is in mesh with the gear 20.

To operate the wringer the operator grasps the member 110 and by it lowers the roll 92 so that its ends are receivable in the slots 100 80 of the saddles. The roll 92 is lowered until it rests on the lower roll 90 and the member 110 is swung in one direction or the other so that the stud 122 engages with one of the cams 120. As the member 110 is swung 85 downwardly as before stated, the cam arrangement causes the roll to be moved transversely of the slot so that the part 112 enters a seat 102. By means of the stud and cam and the seat the roll is releasably held in 90 operative relation on the drive roll 90. As the lever 110 is swung to move the roll sideways the yoke 60 is oscillated to cause the driving connections to be engaged.

Whenever it is necessary for the operator 95 to release the roll from operative engagement with the driving roll, all that is necessary is to move the member 110 up or down until the stud 122 rides off the cam 120. As the stud and cam are thus disengaged the roll 100 92 is free to move inwardly. There is a tendency by reason of the normal pressure between the rolls for the upper roll to move inwardly and upwardly whenever the cam and stud are disengaged.

In the event an operator has a hand caught 105 between the rolls and then in some manner contacts with and moves the lever 110 up or down the upper roll will by reason of the pressure exerted thereagainst move upwardly 110 to instantly release the part caught between the rolls.

It will be noticed the rolls are held in operative engagement by manually releasable 115 means and that the driving connections for the wringer are moved into and out of driving engagement accordingly as the wringer rolls are brought into and out of operative engagement.

According to the form of the invention shown in Fig. 5, the roll 92 is released by an upward movement only of the member 110. In such a case a cam face 160 extends downwardly from the upper end of the saddle 125 against the bottom of which the stud 122 abuts when the member 110 is in operative position.

Having described the invention in the form 130 at present preferred what we now desire to

claim and secure by Letters Patent of the United States is:

1. A wringer apparatus comprising in combination, a frame, a lower roll rotatable therein, spring pressed members at opposite ends of said frame, a guard having an upper roll associated therewith, the said spring pressed members being provided with receiving means for receiving said guard and upper roll so that said roll may rest on said lower roll with the axes of said rolls in a certain plane, the said receiving means being arranged to permit the upper roll in contact with the lower roll to be moved circumferentially of said lower roll so that the axes of said rolls are in a different plane from said certain plane, and releasable connections associated with said guard and spring pressed members to releasably hold said rolls in operative engagement.

2. A wringer apparatus comprising in combination, a frame, a lower roll rotatable therein, a guard having an upper roll pivoted therein, driving connections for one of said rolls including a shiftable part for engaging and disengaging said driving connections, spaced members on said frame for removably receiving said guard and upper roll whereby said upper roll may rest on said lower roll with the axes of said rolls disposed in a certain plane, releasable connections associated with said members and guard arranged to permit the guard to swing on its pivotal connection with said upper roll and move the guard and upper roll about the axis of the lower roll and releasably hold said upper roll in operative engagement with said lower roll wherein the axes of the rolls are disposed in a plane angular to said certain plane.

3. A wringer apparatus comprising in combination, a frame, a lower roll rotatable therein, a guard having an upper roll pivoted therein, driving connections for one of said rolls including a shiftable part for engaging and disengaging said driving connections, spaced members on said frame for removably receiving said guard and upper roll whereby said upper roll may rest on said lower roll with the axes of said rolls disposed in a certain plane, releasable connections associated with said members and guard arranged to permit the guard to swing on its pivotal connection with said upper roll and move the guard and upper roll about the axis of the lower roll and releasably hold said upper roll in operative engagement with said lower roll wherein the axes of the rolls are disposed in a plane angular to said certain plane, a movable part for actuating said shiftable part adapted to receive said guard and be moved by swinging movements of the guard.

4. A wringer apparatus comprising in combination, a frame, a lower roll rotatable

therein, a guard having an upper roll pivoted thereto, driving connections for one of said rolls having a shiftable part for engaging and disengaging said connections, spaced spring pressed members on said frame provided with slots for removably receiving the ends of said guard whereby said upper roll may rest on said lower roll with the axes of said rolls disposed in a certain plane, the said slots permitting the guard to be swung on its pivotal connection with said upper roll to a tilted position, means associated with said members and guard operable as the guard is swung to move said upper roll circumferentially of said lower roll and to releasably hold said roll in operative engagement with said lower roll wherein the axes of the rolls are in a plane at an angle to said certain plane and an oscillatable member for receiving said guard which is operable by the swinging thereof to actuate said shiftable member.

5. A wringer apparatus comprising in combination, a frame, driving connections including a shiftable member for engaging and disengaging said connections, a lower roll removably connected to said connections, a guard having an upper roll pivoted therein, spaced members yieldingly mounted on said frame provided with guard receiving parts whereby the upper roll may rest on said lower roll with the axes of said rolls disposed in a certain plane, the said parts permitting the guard to be swung on its pivotal connection with said upper roll to a tilted position, means associated with said spaced members and guard operable as the guard is swung to move said upper roll circumferentially of said lower roll and to releasably hold said roll in operative engagement with the lower roll with the axes of said rolls in a plane angular to the said certain plane, an oscillatable member for receiving said guard which is operable by swinging movements thereof and is connected to said shiftable member and a part associated with said guard which extends along said wringer in front of the rolls when the guard is in a tilted position.

6. A wringer apparatus comprising in combination, a frame, a drive member, a shiftable driven member and an oscillatable member for shifting the same, a lower roll removably connected to said driven member, spring pressed members on said frame, a guard and upper roll pivotally connected, the said spring pressed members and a part associated with said oscillatable member formed to receive said guard whereby said upper roll may rest on the lower roll with the axes of said rolls in a certain plane and adapted to permit swinging of said guard, cam means associated with said guard and one of said spring pressed members adapted accordingly as the guard is swung to move said guard and upper roll circumferentially

of the lower roll and releasably lock said guard and member in operative relation with the axes of said rolls in a plane disposed angularly to said certain plane.

5 7. A wringer apparatus comprising in combination, a support including a part for driving mechanism and a frame, a drive member associated with said first-named part and a driven member reciprocable for engaging the same, an oscillatable and reciprocable member for actuating said driven member, means associated with said first-named part and oscillatable member to bring about reciprocation thereof as it is oscillated, a lower roll removably connected to said driven member, a guard and upper roll pivoted therein, spring pressed members on said frame and a yoke associated with said oscillatable member for receiving said guard whereby the upper roll may rest on said lower roll and adapted to permit the guard to swing on its pivotal connection with said upper roll and cam means associated with said spring pressed member and guard adapted to move the guard and oscillate the yoke and roll circumferentially of said lower roll as the guard is swung and to releasably lock said guard in operative position.

8. A wringer apparatus comprising in combination, a support including a part for driving mechanism and a frame for a wringer, a drive member and a reciprocable driven member for engaging the same, an oscillatable and reciprocable shift member for reciprocating said driven member, cam means associated with said first-named part and said shift member adapted to cause reciprocation of the latter as it is oscillated, a second oscillatable member operatively connected to said shift member, a drive roll removably connected to said driven member, a pivotally connected guard and driven roll, spring pressed members on said frame and a yoke associated with said second oscillatable member formed to receive said guard and driven roll whereby the same may rest on said drive roll and adapted to permit swinging movements of said guard on its pivotal connection with said driven roll and cam means associated with said spring pressed members and guard adapted as the guard is swung to move said guard, driven roll and yoke about the axis of the drive roll and releasably lock said guard in operative position.

9. A wringer apparatus comprising in combination, a support including a part for driving mechanism and a frame for a wringer, a drive member and a reciprocable driven member for engaging the same, an oscillatable and reciprocable shift member for reciprocating said driven member, cam means associated with said first-named part and said shift member adapted to cause reciprocation of the latter as it is oscillated, a second oscillatable member operatively connected to said shift member, a drive roll removably connected to said driven member, a pivotally connected guard and driven roll, spring pressed members on said frame and a yoke associated with said second oscillatable member formed to receive said guard and driven roll whereby the same may rest on said drive roll and adapted to permit swinging movements of said guard on its pivotal connection with said driven roll and cam means associated with said spring pressed members and guard adapted as the guard is swung to move said guard, driven roll and yoke about the axis of the drive roll and releasably lock said guard in operative position.

cation of the latter as it is oscillated, a second oscillatable member operatively connected to said shift member, a drive roll removably connected to said driven member, a pivotally connected guard and driven roll, 70 spring pressed members on said frame and a yoke associated with said second oscillatable member formed to receive said guard and driven roll whereby the same may rest on said drive roll and adapted to permit swinging movements of said guard on its pivotal connection with said driven roll and cam means associated with said spring pressed members and guard adapted as the guard is swung to move said guard, driven roll and yoke about the axis of the drive roll and releasably lock said guard in operative position, a drain board mounted for tilting movements in said frame and connections between the same and said yoke whereby the drain board is tilted by oscillation of the yoke.

10. A wringer apparatus comprising in combination, a support including a part for driving mechanism and a frame for a wringer, a drive member and a reciprocable driven member for engaging the same, an oscillatable and reciprocable shift member for reciprocating said driven member, cam means associated with said first-named part and said shift member adapted to cause reciprocation of the latter as it is oscillated, a second oscillatable member operatively connected to said shift member, a drive roll removably connected to said driven member, a pivotally connected guard and driven roll, 90 spring pressed members on said frame and a separate yoke associated with said second oscillatable member formed to receive said guard and driven roll whereby the same may rest on said drive roll and adapted to permit swinging movements of said guard on its pivotal connection with said driven roll and cam means associated with said spring pressed members and guard adapted as the guard is swung to move said guard, driven roll and yoke about the axis of the drive roll and releasably lock said guard in operative position, a drain board mounted for tilting movements in said frame and connections between the same and said yoke whereby the drain board is tilted by oscillation of the yoke and means for releasably locking said shift member in a certain position.

11. A wringer apparatus comprising in combination, a support, a driving element and a reciprocable driven element engageable therewith, a cam member actuating said driven element oscillatable and reciprocable in said support, yokes oscillatable in said support in spaced relation one of which is connected to said cam member, a lower roll in said yokes, the said yokes being provided with slots for receiving a guard and upper roll, a guard having an upper roll rotatable 120 125 130

- therein, receivers yieldingly mounted on said support adjacent said yokes having slots for receiving said guard and upper roll with the said roll resting on the lower roll adapted to permit said guard to be tilted to move the upper roll circumferentially of the lower roll and cam mechanism associated with said guard and slots to releasably lock the guard to said receivers in tilted operative position with the axis of the upper roll at a side of a perpendicular line through the axis of the lower roll and connections between one of said rolls and said driven element.
12. A wringer apparatus comprising in combination, a support, a driving element and a reciprocable driven element engageable therewith, a cam member oscillatable and reciprocable in said support, yokes oscillatable in said support in spaced relation one of which is connected to said cam member, a lower roll in said yokes, the said yokes being provided with slots for receiving a guard and upper roll, a guard having an upper roll rotatable therein, receivers yieldingly mounted on said support adjacent said yokes having slots for receiving said guard and upper roll with the said roll resting on the lower roll adapted to permit said guard to be tilted to move the upper roll circumferentially of the lower roll and cam mechanism associated with said guard and slots to releasably lock the guard to said receivers in tilted operative position with the axis of the upper roll at a side of a perpendicular line through the axis of the lower roll, connections between one of said rolls and said driven element, the said yokes being oscillatable on the axis of said lower roll.
13. A wringer apparatus comprising in combination, a housing and a wringer frame, a driving member and a reciprocable driven member engageable therewith, a cam member reciprocable and oscillatable in said housing for shifting said driven member, cam and slot connections between said cam member and housing to bring about reciprocation of the cam member as it is oscillated, a pair of spaced yokes associated with said housing and frame for oscillation therein arranged in spaced relation and being provided with slots, a lower roll therein, receivers adjacent said yokes yieldingly mounted at opposite ends on said frame having receiving slots therein, a guard and an upper roll receivable in the slots of said receivers and yokes adapted for tilting movements with the roll resting on the lower roll so the upper roll may move circumferentially of the lower roll and cam mechanism associated with the guard and slots of the receivers to releasably lock the guard in operative tilted position, connections between one of said yokes and said cam member and connections between one of said rolls and said driven member, and means for releasably locking said cam member in a certain position.
14. A wringer apparatus comprising in combination, a housing and a wringer frame, a driving member and a reciprocable driven member engageable therewith, a cam member reciprocable and oscillatable in said housing for shifting said driven member, cam and slot connections between said cam member and housing to bring about reciprocation of the cam member as it is oscillated, a pair of spaced yokes associated with said housing and frame for oscillation therein arranged in spaced relation and being provided with slots, a lower roll therein, receivers adjacent said yokes yieldingly mounted at opposite ends on said frame having receiving slots therein, a guard and an upper roll receivable in the slots of said receivers and yokes adapted for tilting movements with the roll resting on the lower roll so the upper roll may move circumferentially of the lower roll and cam mechanism associated with the guard and slots of the receivers to releasably lock the guard in operative tilted position, connections between one of said yokes and said cam member and connections between one of said rolls and said driven member, the said yokes being oscillatable on the axis of the lower roll.
15. A wringer apparatus comprising in combination, a housing and a wringer frame, a driving member and a reciprocable driven member engageable therewith, a cam member reciprocable and oscillatable in said housing for shifting said driven member, cam and slot connections between said cam member and housing to bring about reciprocation of the cam member as it is oscillated, a pair of spaced yokes associated with said housing and frame for oscillation therein arranged in spaced relation and being provided with slots, a lower roll therein, receivers adjacent said yokes yieldingly mounted at opposite ends on said frame having receiving slots therein, a guard and an upper roll receivable in the slots of said receivers and yokes adapted for tilting movements with the roll resting on the lower roll so the upper roll may move circumferentially of the lower roll and cam mechanism associated with the guard and slots of the receivers to releasably lock the guard in operative tilted position, connections between one of said yokes and said cam member and connections between one of said rolls and said driven member, the said yokes being oscillatable on the axis of the lower roll.
16. A wringer apparatus comprising in combination, a support, means for driving a roll including a shifting member reciprocable and oscillatable relative to said support, means associated with said support and shifting member to bring about reciprocation of the latter as it is oscillated, a frame having receiving slots, an oscillatable member connected to said shifting member, a lower roll

in said frame, a guard and pivotally mounted upper roll receivable in said slots, connections between one of said rolls and said driving means, the said slots and guard being 5 adapted to permit the guard to tilt and the upper roll to move circumferentially of the lower roll and arranged whereby the guard is releasably locked in said frame and a part of said oscillatable member and said guard 10 being engageable whereby the said member is oscillated by tilting of the guard.

17. A wringer apparatus comprising in combination, a support, a pair of rolls, engageable driving means for one of said rolls 15 including an oscillatable and reciprocable shifting member to engage and disengage the same, means associated with said support and shifting member to bring about reciprocation of the latter as it is oscillated, an oscillatable 20 member connected to said shifting member, a guard associated with one of said rolls mounted to tilt between operative and in-operative positions and move said roll circumferentially of the other roll and connections 25 between the guard and oscillatable member whereby the shiftable member is operated by movements of the guard.

In testimony whereof we affix our signatures.
